UNITED STATES PATENT OFFICE

EARL M. HICKS, OF LEBANON, INDIANA

AIR CLEANER AND HUMIDIFIER

Application filed June 14, 1932. Serial No. 617,211.

This invention relates to an improved apparatus for cleaning and humidifying air, especially designed for use in connection with the air intake of a hot air furnace and in other places where it is desired to moisten and remove impurities from supplies of air.

The primary object of the present invention is to provide an apparatus of the above kind which is simple and compact in construction, reliable in operation, and efficient in properly cleaning and humidifying the air passing therethrough.

A more specific object of the present invention is to provide an air cleaner and humidifier of the above kind embodying an air moistening and cleaning device which includes an endless moving web and means for keeping the web saturated with water to effectively clean and moisten the air passing therethrough, the web forming part of a bodily removable unit so that the web may be conveniently renewed or cleaned from time to time as found necessary.

A further object of the invention is to provide the removable unit with a novel arrangement of baffles for removing excess moisture from the air and thereby preventing the air from being supplied in too wet a condition.

Other objects and features of the invention will become apparent from the following description when considered in connection with the accompanying drawings, and the invention consists in the novel form, combination and arrangement of parts herein-after more fully described, shown in the accompanying drawings and claimed.

In the drawings:

Figure 1 is an elevational view of a hot air furnace equipped with an air cleaner and humidifier embodying the present invention.

Figure 2 is an enlarged view partly in section along line 2—2 of Figure 1, and partly broken away.

Figure 3 is a horizontal section on line 3—3 of Figure 2.

Figure 4 is a horizontal section on line 4—4 of Figure 2.

Figure 5 is a vertical section on line 5—5 of Figure 2.

Figure 6 is a side elevational view of the removable web-carrying unit forming part of the air cleaning and moistening means.

Figure 7 is a fragmentary perspective view, showing parts of the unit in Figure 6 prior to assembly and with the web and rollers removed; and

Figure 8 is a wiring diagram.

Referring in detail to the drawings, F indicates a conventional hot air furnace having the usual opening at one side and near the bottom thereof through which cold air to be heated is supplied to the furnace, and having the usual pipes P by which the air, after being heated, is supplied to the various rooms of the building in which the furnace is installed.

As shown, the present invention may be employed for cleaning and humidifying the cold air supplied to the furnace F so that the air, after being heated, will be supplied to the rooms of the building in a clean and properly moistened condition. The invention includes a sheet metal casing 5, the lower portion of which has a front projecting part 6 closed at the top by a hinged lid 7 and provided with a central air outlet 8 at the front thereof adapted to register with the side air inlet of the furnace F when the present device is arranged at one side of the latter as shown in Figure 1. The back portion of casing 5 is divided into upper and lower compartments 9 and 10 respectively by means of a horizontal partition 11, and removably supported in the top of the upper compartment 9 is a filter plate or screen 12 by means of which the larger particles of dust or dirt in the air are initially extracted therefrom. The casing 5 has a hinged door 13 at the back of the upper portion thereof to facilitate access to the filter or screen 12 for its removal.

Mounted upon each end portion of the partition 11 is a blower 14. The blowers 14 have air intakes in the adjacent sides thereof as shown clearly in Figure 4, and are provided with bottom air outlets registered with openings in the ends of the partition 11 so that air may be drawn from the upper compartment 9 and discharged into the lower com-

partment 10 by said blowers. The blowers have a common drive shaft 15 suitably journaled in and extending transversely of the upper compartment 9 as well as projecting through one side of the casing 5, where it is equipped with a large pulley 16 and a small pulley 17. Mounted near the bottom and at one side of the casing 5 is an electric motor 18 having a small pulley 19 on the armature shaft thereof, and passing around the pulley 19 and the pulley 16 is an endless driving belt 20. It will thus be apparent that when the motor 18 is placed into operation the shaft 15 will be driven for operating the blowers 14 so that the air is forcibly drawn from compartment 9 and forced into the lower compartment 10. The compartment 10 has cold air inlets at the top thereof to which cold air may be supplied from the outside through pipes 21 into compartment 9.

Provided in the lower compartment 10 of casing 5 is means for cleaning and humidifying the air as it is delivered to said compartment 10 by the blowers 14 and before it is discharged from said compartment 10 through outlet 8 into the air jacket of the furnace F. As shown, this means consists of a water pan 22 arranged upon the bottom 30 of the casing 5, and a removable web carrying unit 23 positioned in the front projecting part 6 of the casing. This unit consists of a suitable frame in which are journaled upper and lower rollers 24 and 25 around which passes a highly porous endless fabric web 26, the lower portion of the unit being arranged within the pan 22 so as to submerge the lower roller 25 in the water contained in said pan 22, whereby the web 26 is kept in a moistened condition as it is caused to travel in a manner and by a means to be presently described. As shown, the frame of the unit 23 consists of spaced side channel plates 27 having longitudinal elongated slots 28 in the upper ends thereof in which the ends of the shaft of roller 24 are slidably arranged and journaled. The lower roller 25 has a shaft whose ends are journaled in openings 29 provided in the lower ends of the side plates 27, and it will thus be seen that the upper roller 24 is adjustable away from the lower roller 25 or upwardly to place the web 26 in a taut condition. In order to automatically yieldingly raise the roller 24 to maintain the web 26 taut, levers 30 are hinged to the outer sides of the side plates 27 and extend beneath the projecting ends of the shaft of roller 24, while the free ends of said levers 30 are yieldingly pulled upwardly by means of tension springs 31. In this way the roller 24 is yieldingly urged away from roller 25 so as to automatically tighten or maintain the web 26 in a taut condition. It is noted that the side plates 27 are removable from the ends of the 65 roller shafts so that access to the web 26 may

be readily had to facilitate its removal from the rollers upon forcing the roller 24 downwardly toward the roller 25 against the action of springs 31. Arranged between the side plates 27, as well as between the runs of the 70 web 26 is a baffle plate assembly including side plates 32 removably fitted in the side plates 27 between the shafts of the rollers 24 and 25, and horizontal spaced baffle plates 33 rigidly connecting the side plates 32 and 75 inclined rearwardly and downwardly, as well as having upwardly and rearwardly turned forward edges and downwardly turned rear edges as shown clearly in Figures 5 and 7. The purpose of these baffle plates is to remove 80 excess water or moisture from the air after it passes through the rear run of web 26 to the outlet 8, and to cause the removed excess water to drip back into the pan 22, whereby the heated air supplied to the rooms 85 will not be laden with an excessive amount of moisture. It will be noted that the upright air cleaning and moistening unit 23 may be bodily removed upwardly from the compartment 10 when the lid 7 is opened, should the same be found desirable at any 90 time for renewal or repair purposes. To retain the parts against easy separation, the lower ends of the side plates 32 are provided with longitudinal elongated slots 34 so as to 95 fit down over the projecting ends of the shaft of the lower roller 25. Cleats 35 are secured to the top and sides of the casing 5 within compartment 10 and in rearwardly spaced relation to the front of the casing so as to form 100 in conjunction with the front wall of the latter a vertical guideway in which the unit 23 is slidably positioned and by which it is properly guided when inserted in or removed from the casing. In addition, the cleats 35 prevent passage of the air around the unit 23 and direct the air through the web 26 before 105 passing to outlet 8. A forwardly and downwardly curved baffle 36 is also provided at the back of the casing 5 within compartment 110 110 to assist in directing the air forwardly through the web 26.

Mounted on one side of the casing 5 is a reducing gearing generally indicated at 37 having a driven shaft 38 projecting inwardly 115 through the adjacent side of casing 5 for operative connection with the adjacent end of the shaft of roller 25. The inner end of driven shaft 38 is longitudinally slotted, and the adjacent end of the shaft of roller 25 is 120 flattened as at 39. Thus, by positioning driven shaft 38 with its slot vertical, the end 39 of the shaft of roller 25 may be engaged in the slot of shaft 38 when the unit 23 is lowered into place, thereby establishing 125 a driving connection between the shaft 28 and the shaft of roller 25. At the same time, with the parts similarly positioned, the unit 23 may be readily removed as permitted by free passage of the end 39 of the shaft of 130

roller 25 out of the slot of the driven shaft 38 of reducing gearing 37. The gearing 37 also includes a driving shaft 40 on which is secured a large pulley 41, and passing about the pulley 41 and the pulley 17 on the blower shaft 15 is an endless driving belt 42. It will thus be seen that when the motor 18 is placed into operation for driving the blowers 14, the roller 25 will also be driven at a slow speed so as to cause the web 26 to travel slowly in the direction of the arrow in Figure 5. In this way the web 26 is kept saturated with water from pan 22, and fresh portions of the web are constantly brought into the path of the air passing through the casing 5 so that said air is properly cleaned and moistened.

Any suitable means may be provided for supplying water to the pan 22 and maintaining the water at a predetermined level within said pan. I have shown a water supply pipe 43 adapted to connect with the city water supply and having a float valve on the end thereof arranged to discharge into the pan 22 as indicated at 44 in Figures 2 and 3. The float of valve 44 is arranged to depend in the pan 22 so as to rise and fall with the level of the water in the latter, thereby cutting off the supply of water when the latter reaches a predetermined level in pan 22 and opening the valve to supply additional water when the level of the same in the pan 22 lowers below such predetermined level. The float of valve 44 may be adapted for upward adjustment out of the path of pan 22 whenever insertion or removal of said pan is desired. In order to facilitate introduction or removal of the pan from the casing 5, the latter has a door in the back thereof adjacent the bottom of the same as clearly shown at 45 in Figures 1 and 5.

The apparatus may be controlled in various ways, but I have shown the motor 18 automatically controlled by a thermostatic switch 46 placed in the head of the furnace 5 so as to start the air conditioner automatically at certain temperatures of the furnace. I have also shown the current supplied from a main line at 47 controlled by a main line switch 48, and also by a manually operable by-pass switch for manual control of the apparatus when in operation in the summer or warm weather. As these devices are commonly employed in the control of air conditioners, they are not described herein more in detail and form no specific part of the present invention.

As will be clearly seen in Figure 4, the blowers 14 are spaced apart, and provided in the partition between these blowers is an opening controlled by a sliding damper 50. Whenever conditions render cleaning and moistening of the air unnecessary, temporarily, or should the apparatus be temporarily out of commission for repair, the unit 23

and filter 12 may be removed and the damper 50 opened so as to allow a direct flow of cold air through the apparatus into the air jacket of furnace F and thence to the rooms of the building. This will obviate the necessity of dismantling the apparatus or disturbing its operative relation to the furnace. 70

It will be seen that when the motor 18 is placed into operation the blowers 14 will draw air into the casing 5 and force it into and through compartment 10 and out through outlet 8 for positive passage through the air jacket of the furnace and thence through pipes P into the rooms of the building. As the air passes from compartment 10 to outlet 8, it is caused to pass through the web 26, and due to the moistened condition of the latter, impurities are extracted from the air by said web and moisture is taken up by the air from said web. Excess moisture is removed from the air before entering the furnace by means of the baffles 33, and due to the traveling of web 26, fresh portions of the latter are constantly being presented to the air passing through the casing 5. It will thus be seen that I have provided a simple and efficient apparatus for cleaning and humidifying air which may be conveniently installed and readily maintained in an efficient operative condition.

Minor changes are contemplated within the spirit and scope of the invention as claimed.

What I claim as new is:

1. In an air conditioning apparatus of the class described, a casing having an air inlet and an air outlet, an open top water pan within said casing, an air cleaning and moistening unit mounted in the casing between the air inlet and the air outlet and including an endless traveling web arranged to be moistened by the water in said pan, said unit being slidably mounted in the casing to facilitate insertion and removal of the same, means for forcing air through the casing and driving said web, and a baffle plate assembly interposed between the runs of said web for removing excess moisture from the air after passing through one run of the web and before leaving the casing. 100 105 110

2. In an air conditioning apparatus of the class described, a casing having an air inlet and an air outlet, an open top water pan within said casing, an air cleaning and moistening unit mounted in the casing between the air inlet and the air outlet and including an endless traveling web arranged to be moistened by the water in said pan, said unit being slidably mounted in the casing to facilitate insertion and removal of the same, means for forcing air through the casing and driving said web, and a baffle plate assembly interposed between the runs of said web for removing excess moisture from the air after passing through one run of the web and before leaving the casing, said baffle plate as- 130

sembly including side plates connected by spaced horizontal baffles inclined upwardly toward the air outlet and having upwardly and rearwardly directed upper edges.

3. In an air conditioning apparatus of the class described, a casing having a top air inlet and a front air outlet, the lower portion of the casing having a projecting front part closed by a lid, an open top water pan arranged upon the bottom of the casing, an air cleaning and moistening unit vertically slidably in the forward projecting part of the casing for bodily insertion or removal when said lid is opened, said unit comprising a frame having upper and lower rollers journaled therein and an endless web passing about said rollers, the lower roller being normally submerged within the water pan whereby the web is moistened by the water in said pan when caused to travel, a driven shaft projecting through one side of and into the casing, and means to effect a driving connection between said driven shaft and the lower roller of the unit when the latter is operatively positioned within the casing.

4. In an air conditioning apparatus of the class described, a casing having a top air inlet and a front air outlet, the lower portion of the casing having a projecting front part closed by a lid, an open top water pan arranged upon the bottom of the casing, an air cleaning and moistening unit vertically slidably in the forward projecting part of the casing for bodily insertion or removal when said lid is opened, said unit comprising a frame having upper and lower rollers journaled therein and an endless web passing about said rollers, the lower roller being normally submerged within the water pan whereby the web is moistened by the water in said pan when caused to travel, a driven shaft projecting through one side of and into the casing, means to effect a driving connection between said driven shaft and the lower roller of the unit when the latter is operatively positioned within the casing, a partition dividing the rear portion of the casing into upper and lower compartments and provided with a central opening, a damper for closing said central opening, spaced blowers mounted in the casing above said partition, said partition having further openings in the end portions thereof registered with the outlets of said blowers, and means for driving the blowers and said driven shaft.

5. In an air conditioning apparatus of the class described, an air cleaning and moistening unit adapted to be partially submerged in water and comprising side frame plates having rollers journaled in the upper and lower portions thereof, one of the rollers being movable toward and from the other roller, means to yieldingly urge said one roller away from the other roller, an endless web passing about said rollers and adapted to be maintained in

a tightened condition by the movement of said one roller away from the other roller, a baffle plate assembly interposed between the rollers and the runs of said web, said baffle plate assembly including side plates arranged between the first-named side plates and the rollers, and horizontal baffle plates rigidly connecting the last-named side plates, said baffle plates being inclined downwardly from one run of the web toward the other run thereof and having upwardly and inwardly directed upper edges.

6. In an air conditioning apparatus of the class described, a casing having a top air inlet and having the rear portion thereof divided into upper and lower compartments by means of a horizontal partition, the lower portion of the casing having a forwardly projecting part provided with an air outlet in the front wall thereof, said projecting part further having an open top closed by a lid, a baffle at the back of the lower compartment extending downwardly and forwardly toward the air outlet, an open top water pan arranged upon the bottom of the casing beneath said baffle, an air moistening and cleaning unit resting upon the bottom of the pan and arranged in the projecting part of the casing for bodily insertion through the top thereof when the lid is opened, said unit comprising a pair of spaced rollers and an endless web passing about said rollers, a driven shaft, means to establish a driving connection between the lower roller and said driven shaft when the unit is operatively positioned within the casing, a blower in the upper compartment of the casing, said partition having an opening registered with the outlet of the blower, and means for driving said blower and said driven shaft.

In testimony whereof I affix my signature.
EARL M. HICKS.
